UNITED STATES PATENT OFFICE

GEORGE W. BINNS, OF CINCINNATI, OHIO, ASSIGNOR TO CINCINNATI GRINDERS INCORPORATED, OF CINCINNATI, OHIO, A CORPORATION OF OHIO.

GRINDING MACHINERY.

Application filed November 22, 1926. Serial No. 149,838.

This invention relates to improvements in grinding machinery and has particular reference to a machine adapted for use in the production of spherical articles such as balls for ball bearings, in which both extreme rapidity of production and accuracy of finished product is requisite.

One of the objects of the present invention is the provision of an improved mechanism which will make possible the accurate rapid grinding of spherical articles, together with a control of the size adjustment capable of operation during grinding.

A further object of the present invention is the provision of an improved mechanism for operation on spherical articles in a continuous stream, which shall cause said articles to be subjected to a maximum of grinding action during the period of their passage through the machine.

Another object of the invention is the provision of a machine which will make possible the grinding of spherical articles simultaneously in a plurality of intersecting planes to cause a break-up of the cutting lines of force exerted on the article, and which shall at the same time make it possible to relatively control the article to be ground, so that a true spherical form may be generated thereon by the combined grinding machines.

Additional objects and advantages of the present invention should be readily apparent by reference to the accompanying drawings illustrating one embodiment thereof, and it will be understood that I may make any modifications in the specific structural details hereinafter described within the scope of the appended claims, without departing from or exceeding the spirit of the invention.

Figure 1 is a side elevation of a grinding machine embodying my improvements.

Figure 2 is a vertical sectional view through the machine.

Figure 3 is a transverse section taken on the line 3-3 of Figure 2.

Figure 4 is a detail sectional view of the work feeding mechanism.

Figure 5 is an enlarged section through the work throat, and,

Figure 6 is a fragmentary sectional view illustrating the contoured wheel adjustment mechanism.

In the drawings the numeral 10 designates

the bed or base of a grinding machine of what is known as the general centerless type. 55 Mounted on this base for in and out movement is the grinding wheel slide 11, whose position may be adjusted as by the pilot wheel 12. This slide has the spindle 13 for the grinding wheel 14, fitting within the hood or 60 casing 15. Power is applied through chain 16, gears 17 and shaft 18. Shaft 18 in turn has a sprocket 19 driving the chain belt 20 which operates shaft 21. A second grinding wheel 22 is carried by shaft 21 and has a contoured edge 23, the central portion of which is of the curve to be produced on the finished work piece.

It will be noted the wheel 22 is of diameter to project upward and be disposed adjacent 70 the periphery of the grinding wheel 14, somewhat below the axis of its spindle 13. Mounted on the bed is a second slide 24, bearing an angularly adjustable head 25, in which is mounted the spindle 26 for regulating wheel 75 27 which may thus be set at an angle to the operative face of the grinding wheel 14. In and out adjustment of slide 24 is effected as by screw 28 bearing worm gear 29 in mesh with worm 30 rotatable through pilot wheel 80 31, whereby slight increments of advancing or receding movement may be imparted to the regulating wheel to adjust its position with respect to that of the two grinding wheels just referred to.

The three wheels just described together form a combined work supporting, guiding, controlling and grinding mechanism in which the sphere to be accurately reduced and rounded to within the accurate limits of a 90 fractional thousandth of an inch may be properly produced. This sphere 32 is suitably supplied to the grinding throat as at 33 between the wheels 14 and 27 and resting upon and supported by the wheel 22. While 95 the wheel 22 may be operated either with the direction of feed of the balls 32 through the machine or opposed to it, most desirable results can be accomplished if the wheel rotates in a clockwise direction as indicated by the 100 arrow in Figure 3, and the balls move from front to rear of the machine. The balls will therefore be moved against the grinding thrust of the contoured wheel 22 and are preferably forcibly so shifted by suitable feeding mechanism. Inasmuch as they are disposed 105

in grinding throat between the other two wheels and below the plane of axes of said wheels, as is clearly shown in both Figures 2 and 5, it will be impossible for them to 5 properly move upward. Also, this tendency toward upward movement is counteracted by the downward thrust of wheel 14 which moves in the direction of the arrow shown in Figure 5, or with its operative face thrusting the 10 balls against wheel 22. It will be understood that both wheels 14 and 22 are operated at a relatively high or grinding speed as for example a surface speed of 6000 or 7000 feet per minute, while the third wheel 27 moves 15 upwardly at a speed of 50 to 100 feet per minute for example. With this operation the wheels 14 and 22 both exert a cutting action or thrust against the ball in planes at right angles to each other, while the wheel 20 27 moving upwardly at its point of contact as indicated by the arrow thereon, regulates and controls the rotation of the ball. At the same time this wheel is preferably set at a slight angle to the axis of wheel 14, so that 25 it will exert a transverse diagonal feeding component thrust, tending to push the balls forward and at the same time give them a twisting movement, so that all parts of their surface will be suitably presented to the combined action of the other two wheels.

To produce proper feeding of the work pieces to the grinding throat, any suitable mechanism may be employed. For example, use may be made of a hopper 34 having a discharge tube 35 slotted as at 36. Extended inwardly through this slot may be either a friction drive member, star wheel or the like 37, operated as by sprocket chain 38 from the regulating wheel spindle and moving in a 40 counter-clockwise direction. This member will force the several balls along the tube with a sufficient pressure to counteract the thrust of wheel 22, and cause them to be positively fed through the machine at a slow rate. A 45 trough 39 is disposed in position to receive the balls as they are pushed off wheel 22.

It will thus be seen that by the combined action of a plurality of wheels simultaneously engaging the work piece, both the removal 50 of stock and the speed of rotation and twisting movement of the work piece is properly controlled and effected, so that true spherical articles of prescribed uniform diameter accurate to a fractional thousandth of an inch 55 may be satisfactorily produced.

Inasmuch as the wheel 22 causes the work pieces to pass between wheels 14 and 27 in an arcuate as distinguished from a straight transverse line, it will be understood that 60 these last mentioned wheels in place of having a plain or cylindrical surface, have a surface as indicated at 40, so concaved as to present a line of contact engaging the work piece on opposite sides continuously during its passage through the grinding throat. This sur-

face may be produced by suitable truing mechanism as indicated at 41 and 42.

Similarly, a truing mechanism 43 may be utilized to form the desired contour on the face of wheel 22.

While shaft 21 for wheel 22 has been shown as directly journaled in certain bearings in the bed 10, it is found that in some instances it is desirable to have a certain amount of vertical adjustment for this shaft, as to compensate for different sizes of work or for wear of the grinding wheel. In this event bearings 44 may be contained in slide blocks 45 having diagonally cut lower ends as at 46, each resting on a wedge 47. These wedges 80 for the two bearings 44 may be connected as by the yoke piece 48 engaged by screw 49 swiveled in bed 10 and operable by hand wheel 50. Rotation of this wheel will impart an in or out movement to the connecting yoke 48 and wedges, and thus raise or lower the wheel 22. It will be understood that the several wheel adjusting screws are all provided with suitable dial mechanisms as indicated for example at 51, so that the exact fine 90 degree of adjustment desired may be readily accomplished.

I claim:

1. A grinding machine including a pair of spaced rotary wheels having their operative 95 surfaces moving at different speeds and in opposite directions, and a third rotary member peripherally projecting into the throat between the wheels for supporting work in the throat against the thrust of one of the pair of wheels during grinding.

2. A grinding machine including a pair of spaced rotary wheels having their operative surfaces moving at different speeds and in opposite directions, and a third rotary member peripherally projecting into the throat between the wheels for supporting work in the throat against the thrust of one of the pair of wheels during grinding, said third wheel having a contoured work engaging 100 surface contrageneric to the shape to be produced on the work.

3. A grinding machine including a pair of spaced rotary wheels having their operative surfaces moving at different speeds and 115 in opposite directions, and a third rotary member peripherally projecting into the throat between the wheels for supporting work in the throat during grinding, said third wheel having a contoured work engaging surface and being formed from abrasive material, and means for driving said third wheel at a grinding speed, whereby its contoured surface will be reproduced on the work piece.

4. A grinding machine including a peripherally contoured grinding wheel and a pair of work engaging disks disposed at opposite sides of the grinding wheel, one of said disks having its operative surface driven 130

toward the grinding wheel to exert a thrust component, urging the work against said wheel.

5. A grinding machine including a peripherally contoured grinding wheel and a pair of work engaging disks disposed at opposite sides of the grinding wheel, one of said disks having its operative surface driven toward the grinding wheel to exert a thrust 10 component, urging the work against said wheel, and the other opposed wheel having its operative surface driven in an angularly related path as respects the path of travel of the grinding wheel, whereby a twisting 15 movement will be imparted to work piece engaged by the grinding wheel.

6. A machine of the character described, including a contoured grinding wheel, a pair of work engaging members disposed adjacent the contoured portion of the grinding 20 wheel and shaped to provide a convergent throat spaced from the wheel, whereby the convergence of said throat will limit movement of work pieces in a direction away from 25 the wheel.

7. A machine of the character described, including a contoured grinding wheel, a pair of work engaging members disposed adjacent the contoured portion of the grinding 30 wheel and shaped to provide a convergent throat spaced from the wheel, whereby the convergence of said throat will limit movement of work pieces in a direction away from 35 the wheel, and means for moving one of said convergent throat forming members in a direction toward the grinding wheel, whereby a thrust component is produced, urging the work into engagement with the grinding wheel.

40. 8. A grinding machine including a pair of peripherally opposed members forming a work receiving throat and a grinding wheel having a portion projecting within the throat below the plane of axes of the peripherally 45 opposed members, whereby said members form a convergent throat above the grinding wheel.

9. A grinding machine including a pair of peripherally opposed members forming 50 a work receiving throat and a grinding wheel having a portion projecting within the throat below the plane of axes of the peripherally opposed members, whereby said members form a convergent throat above the grinding 55 wheel, said grinding wheel having a contoured surface contro-generic to that to be produced on the work.

10. A ball grinding machine including a 60 rotating grinding wheel having a concaved peripheral grinding portion, a second grinding wheel having a peripheral portion adapted to correspondingly engage a plurality of work pieces on the contoured periphery of the first mentioned grinding wheel, and a 65 regulating member disposed in opposition to

said grinding wheels for controlling the work engaged thereby.

11. A grinding machine including a pair of grinding wheels having operative portions simultaneously engaging the work in angularly related directions, and a slow moving regulating member constantly urging work pieces in the direction of the grinding wheels. 70

12. A grinding machine including a pair of grinding wheels having operative portions simultaneously engaging the work in angularly related directions, a slow moving regulating member constantly urging work pieces in the direction of the grinding wheels, and means for positively feeding work pieces 75 through the grinding throat provided by the above mentioned parts.

13. A grinding machine including a rotary grinding wheel having a peripherally contoured face, means for urging a work piece in 80 a substantially radial direction toward said face, and additional means for urging a work piece circumferentially of said face.

14. A grinding machine of the character described, including a rotary grinding wheel 90 having a contoured work engaging portion, a second grinding wheel disposed in an angularly related plane for lateral engagement with a work piece on the contoured face of the first grinding wheel, means for retaining the 95 work piece in engagement with said grinding wheels, and additional means for advancing a work piece with respect to the grinding members.

15. A machine for the production of spherical articles, including a rotary abrading member having an arcuate peripheral groove formed circumferentially therein, means for rotating said member at a grinding speed, a second member disposed substantially at 100 right angles to the plane of rotation of the first, means for actuating said second member in the direction of the first at a grinding rate of speed, and a third member in opposition to the said members for retaining a work piece 105 in proper engagement with the operative grinding faces of the first two members.

16. A machine for the production of spherical articles, including a rotary abrading member having an arcuate peripheral groove 110 formed circumferentially therein, means for rotating said member at a grinding speed, a second member disposed substantially at right angles to the plane of rotation of the first, means for actuating said second member 115 in the direction of the first at a grinding rate of speed, a third member in opposition to the said members for retaining a work piece in proper engagement with the operative grinding faces of the first two members, and 120 means for relatively adjusting said members to vary the size of work receiving throat formed thereby.

17. A machine for the production of spherical articles, including a rotary abrading 125

- member having an arcuate peripheral groove formed circumferentially therein, means for rotating said member at a grinding speed, a second member disposed substantially at right angles to the plane of rotation of the first, means for actuating said second member in the direction of the first at a grinding rate of speed, a third member in opposition to the said members for retaining a work piece in proper engagement with the operative grinding faces of the first two members, and means for individually adjusting each of said three members to vary the effective positions of the operative surfaces thereof.
18. A machine for the production of spherical articles, including a rotary abrading member having an arcuate peripheral groove formed circumferentially therein, means for rotating said member at a grinding speed, a second member disposed substantially at right angles to the plane of rotation of the first, means for actuating said second member in the direction of the first at a grinding rate of speed, and a third member in opposition to the said members for retaining a work piece in proper engagement with the operative grinding faces of the first two members, and means for positively urging work pieces in the grinding throat peripherally of the first mentioned member.
19. A machine for producing spherical article, comprising a rotary contoured grinding wheel, a second grinding wheel having its operative surface moving substantially at right angles to the first for simultaneous engagement with a work piece and a third rotary regulating member having its operative surface movable transversely of the direction of movement of one of said grinding members and oppositely as respects the directional movement of the operative surface of the other of said members for regulating the rotary shifting of a work piece, while in joint operative engagement with the two grinding members.
20. A machine for the production of spherical articles including a pair of grinding wheels having operative peripheral portions disposed in angularly related planes, one of said wheels having a contoured surface contrageneric to the shape to be produced upon the work and the other of said wheels having a concave surface formed thereon to insure continuous contact between said surface and a work piece progressing circumferentially of the first mentioned wheel, and a regulating member in joint opposition to said two operative wheel surfaces to maintain contact between the work and said wheel surfaces.
21. A machine for the production of spherical articles including a pair of grinding wheels having operative peripheral portions disposed in angularly related planes, one of said wheels having a contoured surface contrageneric to the shape to be produced upon the work and the other of said wheels having a concave surface formed thereon to insure continuous contact between said surface and a work piece progressing circumferentially of the first mentioned wheel, and a regulating member in joint opposition to said two operative wheel surfaces to maintain contact between the work and said wheel surfaces, said regulating member having its axis tilted with respect to the axis of one of the grinding wheels whereby said regulating member exerts a twisting feed component on the work.
22. A machine for the production of spherical articles including a pair of angularly related grinding members for simultaneous engagement with a work piece in angularly related tangent planes, means engaging the work piece for pressing the work against said grinding members and causing an impositive feeding movement thereof, and additional means for simultaneously exerting a positive feeding component against the work.
23. A grinding machine of the character described including a pair of angularly related grinding wheels operating at grinding rates of speed and a member for joint opposition thereto for maintaining work in engagement with the operative faces thereof, and means for positively shifting the work in a direction which is transverse of the face of one of the grinding members and substantially circumferential of the other of said grinding means, substantially as and for the purpose described.
- In testimony whereof I affix my signature.
GEORGE W. BINNS.
